Patented Nov. 23, 1915.

by *W. S. Horner* At'ty.

UNITED STATES PATENT OFFICE.

WALTER S. HORNER, OF NASHUA, NEW HAMPSHIRE, ASSIGNOR TO NASHUA CARD GUMMED & COATED PAPER COMPANY, OF NASHUA, NEW HAMPSHIRE, A CORPORATION OF MASSACHUSETTS.

PROTECTOR FOR CALENDER-ROLLS.

1,161,676.

Specification of Letters Patent. Patented Nov. 23, 1915.

Application filed May 11, 1915. Serial No. 27,825.

To all whom it may concern:

Be it known that I, WALTER S. HORNER, of Nashua, in the county of Hillsboro and State of New Hampshire, have invented 5 certain new and useful Improvements in Protectors for Calender-Rolls, of which the following is a specification.

This invention relates to machines for the treatment of paper, and refers particularly 10 to what are known as friction calenders. The invention, however, is applicable to any paper treating machine where it is desirable to render it certain that no foreign particles shall pass through the machine adhering to 15 the paper.

When paper is being coated and wound into a coil or roll, foreign substances such 20 as particles of hardened color material, and even tacks or nails, are liable to be wound up in the roll or coil. The paper treating or finishing rolls are frequently very expensive, and it is quite costly if such foreign substances pass along and injure the rolls. This is due not only to the expense of 25 repairs but also to the loss of time in the use of the machine while the repairs are being effected.

My invention consists in the provision of 30 means which, while having no effect whatever upon the paper itself, will act as a barrier to prevent the passage of any foreign particles or substances.

Of the accompanying drawings, Figure 1 is an end view of sufficient parts of a 35 well-known form of calendering machine having my improvements applied thereto, to enable my invention to be understood. Fig. 2 is an elevation from the right of Fig. 1. Figs. 3 and 4 are detail views on 40 a larger scale.

Similar reference characters indicate similar parts in all of the views.

A portion of the frame of the calendering machine is indicated at 12 said frame 45 supporting the friction calender rolls 13, 14, and having brackets 15 to support the supply or unwinding roll of paper *a*. The brackets 15 are provided with side portions or lugs 16 in which are mounted, preferably 50 adjustably, uprights 17 having bearings for a binder roll or lag 18. Another binder roll or lag 19 is supported by brackets carried by frame 12.

As so far described the machine does not

materially differ from a well-known calen- 55 dering machine the roll 14 of which is usually an expensive one, made of compressed cotton. If any foreign particles adhere to the surface of paper *a*, and pass along to the nip of rolls 13, 14, injury is liable to result, 60 either to the rolls or to the paper or both.

To prevent the passage of any objectionable particles, I provide a protector bar or blade 20 which in the machine illustrated in the drawings, is supported by brackets 21 65 adjustably mounted on extensions of the uprights 17, said brackets 21 being held in position vertically on said uprights by means of nuts 22. A bolt or screw 23 at each end of the bar or blade 20 is rigidly 70 secured to a flanged upper edge portion of the blade 20, as by having a reduced portion passing through such flange and secured by the nut 24. The two screws 23 pass through apertures in the brackets 21 75 and are secured tightly by means of nuts 25 and wing nuts 26. In practice the bar or blade 20 is, by means of the adjustable connections just described, set so close to the roll 18 that the paper *a* passing over the 80 roll 18 will just clear the lower straight edge of the bar or blade. In other words, the blade must never contact with the paper itself, or the coating thereon, but must serve merely to arrest, or act as a barrier 85 for, any particles that might adhere to the paper or coating so as to be carried through the machine. The roll 18 and the blade 20 constitute, in effect, opposite walls of a throat through which the paper passes on 90 its way to the treating members of the machine, said throat being narrow (vertically), but slightly exceeding the thickness of the paper and its coating. The edge of the blade 20 is, of course, adjusted so close to 95 the surface of the paper that all projections, such as bits of hardened color or any foreign substances such as tacks, nails, etc., will be removed before the paper passes between the expensive finishing rolls. When such 100 substances are not removed, the finishing rolls are liable to take the impression of such substances when they are hard, and this causes a defect which is, of course, impressed in the paper afterward passing over 105 or between the finishing rolls.

Another advantage of the invention is that if the paper is composed of webs which

are spliced together, with splices of an unusual thickness owing to the end of one web lying on top of the end of the other web, an allowance being also made for the thickness of the paste or glue employed, damage to the rolls due to such thickened portions cannot result because the blade 20 is set at such distance that if an extra thickness of paper comes along, the paper will be automatically torn because the ribbed or extra thickness is arrested by the blade 20. Then the only loss of time resulting is due to that which is required for threading up the machine again. The roll or rolls are not damaged.

20 Webs of paper quite commonly possess certain wrinkles which, by increasing the thickness of the paper, damage the calendering rolls as the splices just described will do. Such wrinkles may run transverse to the web or longitudinal thereof. In either case, however, they are caught by the protector bar or blade 20 and the paper is automatically torn and the roll saved from damage.

25 It is to be understood that I do not limit myself to the specific form of bar or blade 20, or the particular means shown for adjustably supporting it, or its particular location.

30 I claim:

1. A machine having rolls for the treatment of paper and provided with a narrow throat for the passage of the paper on its way to said rolls, said throat being of substantially uniform width from end to end, means being provided to cause the paper to travel with one surface close to but out of contact with one side of the throat.

2. A machine having rolls for the treatment of paper and provided with a barrier

having a straight edge close to the path of travel of the paper but at sufficient distance therefrom to not permit contact of the paper itself therewith, means being provided for holding the barrier rigidly in position to arrest foreign substances.

3. A calendering machine having a support over which the paper passes on its way to be acted upon by the calendering members, and a barrier having a straight edge close to said support but separated therefrom by a space slightly greater than the thickness of the paper.

4. A calendering machine having a support over which the paper passes on its way to be acted upon by the calendering members, and an adjustably mounted barrier having a straight edge close to said support but separated therefrom by a space slightly greater than the thickness of the paper.

5. A calendering machine having a roll over which the paper passes on its way to be acted upon by the calendering members, and a blade mounted above said roll and having means whereby its edge may be adjustably set relatively to said roll.

6. A calendering machine having a pair of uprights, a roll mounted in said uprights for supporting the paper on its way to be acted upon by the calendering members, said uprights having extensions, said extensions having brackets, and a blade adjustably connected with said brackets.

In testimony whereof I have affixed my signature, in presence of two witnesses.

WALTER S. HORNER.

Witnesses:

EDWIN S. GAGE,
WALTER L. BARKER.
